ELECTRIC SWITCH DEVICE

Fred G. Faile, Cleveland, Ohio, assigner to The Leonard Electric Manufacturing Company, Cleveland, Ohio, a corporation of Ohio

Application April 19, 1934, Serial No. 721,349

6 Claims. (Cl. 200—50)

The general object of this invention is to provide an improved electric switch of the double-break multiple-contact type.

A further object is to provide a heavy duty 5 multiple contact electric switch wherein arcing during making and breaking of the circuits is greatly reduced and dangerous arcing eliminated.

A further object is to provide an electric switch 10 the contacts of which must be closed by application of positive manual pressure and rigidly locked in closed position by the same pressure as against being maintained in closed position by resilient or other non-positive means.

A specific object is to provide an improved 15 manually operable electric switch wherein the operations of both opening and closing the circuit or circuits are quickly accomplished manually but independently of the intentional speed of manual operation; in other words, a "fool-proof" switch of this type.

A further object is to provide a "quick-make" 20 and "quick break" switch in which the separable circuit making and breaking elements are forcibly engaged and disengaged without depending 25 upon springs to effect either engagement or disengagement or to maintain engagement.

Still another object is to provide an exceedingly compact industrial multiple contact double-break switch.

A further object is to provide an electric 30 switch wherein the separable contact elements are positively engaged and disengaged by the application of manual pressure and with a wiping wedging action.

A further object is to provide a multiple 35 contact switch and casing wherein the necessary operating elements extend only from the face of the casing, whereby a plurality of switches of the type described may be mounted directly adjacent each other and effectively yet independently operated.

A further object is to provide an industrial 40 multiple contact switch and fuse supporting unit wherein fuses of different capacity and size may be easily and quickly installed by simple adjustment of the parts of the unit.

Still another object is to provide a multiple 45 contact switch including spaced stationary contacts and bridging movable contacts cooperable therewith wherein the movable contacts are so arranged and supported that full electrical contact with the stationary contacts is assured notwithstanding variations in the contacting surfaces and other variations incident to manufacturing 50 the parts on a quantity production basis.

A still further object is to provide a multiple contact switch wherein the electrically independent conductor elements of the switch are more effectively insulated from each other to reduce cross or short circuiting and leakage. 5

Other objects and features will become apparent from the following description wherein reference is made to the drawings. The essential novel characteristics are summarized in the claims. 10

Referring to the drawings:

Fig. 1 is a plan view of the switch and casing, the right hand portion of the casing being broken away to show the construction of certain of the switch parts and fuse supports; 15

Fig. 2 is a sectional view as indicated by the line 2—2 on Fig. 1;

Fig. 3 is a side elevation of the mechanism which will be hereinafter referred to as the switch unit; 20

Fig. 4 is a transverse sectional view of the switch unit taken along the line 4—4 of Fig. 1;

Fig. 5 is a detail view showing some of the parts illustrated in Fig. 3 but in a different relative position; and 25

Figs. 6 and 7 are diagrammatic sectional views showing various relationships between the stationary and movable contact elements of the switch; and

Fig. 8 is a detail view showing a modified 30 arrangement of contacts.

Referring further to the drawings, the casing 1 may comprise a boxlike casing element having a bottom panel 2 and perimetral walls 3 bent up from the base and suitably joined at the corners, 35 the casing being completed by a fixed cover panel 5 and a movable cover panel 6, both panels having perimetral side and end wall flanges 7 adapted to telescopingly engage the side walls 3 of the main casing part. The panel 6 is hinged 40 to the panel 5 as at 8, permitting the panel 6 to be swung outwardly and away from the walls 3 exposing the interior of the casing.

Located within the casing and secured to the base panel 2 is a block 10 of suitable insulation 45 material such as cold molded asbestos composition, this block being secured to the panel 2 as by four screws 11 extending through openings in the cover portions of the block 10 and into threaded bosses 12 in the bottom panel. The 50 block 10 constitutes a unitary rigid base for the switch unit. As shown in Figs. 1, 2 and 4, the block is rectangular in shape and carries at its sides relatively heavy bracket elements 13, preferably sheet metal, these being substantially 55

identical in form. The bracket elements 13 have inwardly extending flanges 15 disposed between the underside of the switch base 10 and the casing panel 2, the bracket elements being secured 5 to the base block 10 by means of the flanges and suitable screws (not shown) extending through the flanges and into suitable threaded inserts (not shown) in the base block.

The outer ends of the bracket elements 13 10 carry ears 16 bent parallel to the flanges 15, the ears being apertured to receive suitable fastening screws, one being shown at 17, Figs. 1 and 2, for securing the fixed panel 5 of the casing cover to the switch unit.

15 The separable contacts of the switch are arranged as follows:

Mounted on the base block 10 are a plurality of stationary electrical contacts 20, (six being present in the illustrated embodiment) these being substantially identical in form and electrical 20 connected to electric service wires in a manner to be hereinafter described. The contacts 20 are arranged in pairs, see Fig. 2, and the contacts of each pair are adapted to be bridged by respective 25 generally V-shaped movable contact elements or blades 22, three being shown (see Fig. 4) carried on a cross head 24 including an insulating cross bar 23 (asbestos composition e. g.) and a metal bar 25 inset into a rectangular channel 27 30 in the outer side of the insulating bar. The bar 25 will be hereinafter referred to as the pressure bar and, being rectangular in cross section and about three times as deep as it is wide, the bar prevents any bending of the cross head such as 35 would tend to make say one of the blades 22 seat or unseat with respect to its contacts 20 ahead of the other blades.

The bar 25 is less wide than the channel 27 wherefore the insulating bar 23 may float slightly 40 with reference to the pressure bar which latter has its ends slidably fitted to parallel slots 26 in the respective brackets 13, the slots guiding the pressure bar for true right line movement in and out to open and close the switch contact elements 45 20 and 22. The pressure bar is secured in the channel 27 by cross pieces 28 (see Figs. 2 and 4) which are, in turn, securely fastened to the insulating bar 23 as by means of screws and threaded inserts (not shown) in the insulation material.

50 The individual sets of movable and stationary contacts and the conductor elements associated with the fixed contacts are effectively separated from each other by barrier strips 30 (hard asbestos board e. g.) and the outermost contacts 55 and conductors, that is, those nearest the bracket elements 13 are insulated from the latter by barrier strips 31, constructed similarly to the barrier strips 30. The contours of the barrier strips 30 and 31 are best illustrated in Fig. 2. The strips 60 have substantially straight inner edges and these rest in grooves 33 in the base block 10, said edges extending the entire length of the base block. The barrier strips, incidentally, greatly strengthen the block against transverse cracking. Each of the strips 30 and 31 is cut out at 34 substantially 65 centrally thereof and rectangularly as shown in Fig. 2 to embrace the insulating cross bar 23. The latter has parallel grooves 35 on its opposite surfaces into which the marginal portions 70 of the barrier strips adjacent the rectangular notches 34 extend.

The tongue and groove relationships just described between the insulating cross bar and the rectangular notches 34 in the barrier strips 30 75 and 31 further insures the electrical independ-

ence of the stationary and movable contacts and conductors of the different sets notwithstanding a considerable accumulation of foreign matter which may be more or less electrically conductive. Likelihood of short or cross circuiting is further 5 rendered negligible by reason of the fact that the overlapping surfaces of the insulation members clean themselves during the operation of the switch to open and closed position, that is during inward and outward throw of the cross head. 10 The arrangement further permits the electrically independent contacts and conductors to be placed closer together, saving space, i. e. permitting greater compactness of construction. Further protection against the accumulation of foreign 15 matter is afforded by cross strips of insulating material 36 and 38 (asbestos board e. g.), see Figs. 1 and 2. These strips are secured to the outer edge surfaces of the barrier strips 30 and 31 as by suitable screws 39 and hold the barrier 20 strips firmly in parallel relationship.

It will be noted in Figs. 2 and 4 that the movable contacts 22 are secured in respective rectangular recesses or troughs 40 on the inward side of the insulating cross bar 23. It will also 25 be noted from Fig. 4 particularly, that the same side of the insulating cross bar is recessed as at 41 for the reception of the barrier strips of insulation 30 and 31. Thus when the insulating cross bar 23 is forced inwardly toward the base 30 block 10, the different sets of contacts and conductors are further insulated from each other against cross circuiting by leakage by overlapping portions of the cross bar and the barrier strips. Likewise, the outermost contacts and conductors are fully insulated from the metal parts 35 of the switch, particularly the brackets 13 and switch operating parts carried thereon.

The movable contacts or blades 22 (as shown in Figs. 6 and 7) each comprises a single V- 40 shaped bar having outwardly extending ears 22', seated at the bottom of the respective rectangular troughs 40. Suitable screws 42, extending inwardly through openings 43 in the insulating bar 23, are threaded into the ears 22' and hold 45 the contact members 22 in fixed position on the insulating bar 23. The stationary contacts 20 are also V-shaped and each comprises spaced contact arms 50, see Figs. 4, 6, and 7, connected by a base loop 51. The base loop is generally rectangular as shown and the bottommost portion is apertured as at 52 to receive attaching screws 53 extending upwardly from the base block in suitable openings therein as shown in Fig. 2. Preferably the arms 50 are buttressed by generally 50 U-shaped spring members 55, the arms of which extend in embracing relation to the contact arms 50. The bases of the spring members are likewise apertured to receive the screws 53. The screws threadingly engage openings 56 in 60 conductor bars 57 and 57'.

Referring to Fig. 6, it will be noted that the angularity between the arms of the V-shaped movable contacts or blades 20 and the resilient arms 50 of the fixed contacts is dissimilar, the 65 angle between the arms 50 being smaller. The purpose of this is to provide a yielding wedging and sliding contact between the arm portions of the contacts 20 and 22 as the same are brought together. Fig. 6 illustrates in broken lines at 70 22x the condition when the contacts 20 are first brought into engagement with the arms 50 and in Fig. 7, the full contact position with respect to both contacts is shown.

As shown in Fig. 2, the conductor bars 51 (one 75

being shown) extend to suitable detachable conductor wires 58 secured as by screws 59 to threaded metallic inserts 59' in the base block. The bars 57' extend from the respective contacts 20 and are electrically associated with suitable fuse clips 60, see Figs. 1 and 2. The fuse clips 60 are of conventional construction and may be secured to the base block 10 by suitable screws 61 engaging threaded inserts 61' in the base block.

A fuse of conventional type adapted to be supported by clips such as 60 is shown in Fig. 1 at F. Each of the fuses has one of its ends supported by one of the clips 60, just described, and the opposite end by one of a series of similar fuse clips 62 (one being shown) connected with conductor wires 63. The clips 62 and connections are carried on a common insulating block 65 secured to the base panel 2 of the switch casing as by suitable screws 67. The block may be positioned as illustrated in Fig. 1 or, if it is desired that a shorter fuse (of less capacity) be employed, then the block 65 may be moved toward the base block 10 of the switch, the screws 67 then entering other openings, one of which is shown at 68, Fig. 1, in the casing panel 2. This adjustment may be done by means of a screw driver without having to remove the casing 1 from the wall or to disturb the switch unit.

The operating mechanism for the cross head 24 is best shown in Figs. 1, 3 and 5. Supported on a suitable rock shaft 70 mounted in the brackets 13 are a pair of pressure bar operating cams 72 and 73. One of these operating cams, namely 73, has an extension 74 passing outwardly through a slot 5a in the fixed portion 5 of the casing cover and this extension 74 carries an operating handle 75, mounted on a suitable pin 76, by which the operating cams are turned manually to move the cross head. The extension 74 also has an arm 74a (Fig. 3) projecting into closely overlying relation to the movable cover panel 6 when the switch is closed whereby opening of this cover panel about its hinges 8 automatically opens the switch contacts. Openings 74b and 74c may also be provided in the cam extension 74 for the purpose of permitting the cam to be locked (as with a padlock) with the switch contacts in open or closed position as desired.

Preferably the pressure bar operating cams have non-circular openings 71, one only being shown, embracing complementary non-circular end portions of the rock shaft 70 and the cam may be held onto said non-circular shaft portions by suitable cotter pins as shown. The opposite ends of the pressure bar 25 have substantially cylindrical pins 78 preferably integral therewith and extending through cam slots 79 in the respective cams 72 and 73. The slots are identical in contour and the contour is best illustrated in Fig. 5. The pressure bar pins 78 carry suitable hardened rollers 80 which ride on the cam surfaces of the slots 79 which will now be described.

Each cam slot 79 has a portion 79a extending generally radially from the axis of the rock shaft and a circumferentially extending portion 79b, the latter portions forming retaining shoulders 79c for the respective rollers 80. When the switch contacts 20 are in the open position, illustrated in Figs. 2 and 4, the rollers 80 occupy the radial portions 79a of the cam slots and when the contacts are closed, see Figs. 3 and 7, the

rollers occupy the circumferentially extending portions 79b of the cam slots and are retained in this position, see Fig. 3, by the shoulder 79c. The path of the shoulder 79c intercepts a portion of the normal path of the roller while the roller is traveling along such portion and consequently the roller must be slightly stressed out of its normal path by the shoulder to pass the same, whereupon it lies in the portion 79b as shown in Fig. 5 and must remain in this position due to the fact that the circumference of the roller is closer, at a point beyond the shoulder, to the pivotal axis 70 than is the point of contact of the shoulder with the roller circumference. This accomplishes the desired result of holding the blades and contacts 22 and 20 firmly in full contact against accidental dislodgment and assists in the quick making and breaking operations of the switch by interposing a "hazard" with respect to both operations. Various parts of the switch are subject to substantial stresses as the rollers ride from one portion of the cam slots to the other but the parts so subjected are sturdily built to withstand the strains and the rollers and cams are hardened to withstand the wear.

The cross head 24 is normally biased into open position by suitable springs 82 and levers 83, the springs being connected to the respective bracket elements 13 and to the levers 83, as shown in Fig. 3. The levers are pivoted to suitable fixed pins 84 on the brackets 13 and have slots 85 embracing the pins 78 of the pressure bar. As will be seen from Fig. 3, the springs 82 tend, on contracting, to throw the pressure bar to switch contact releasing position. These springs and levers 82 and 83 accomplish "quick breaking" of the contacts at 20 and 22 as soon as the pressure bar operating cams are turned to move the rollers 80 beyond the shoulders 79c. The manual force necessarily required to release the rollers adds to the quick breaking action of the springs 82.

In order that the operator cannot hold back the cross head against the quick breaking action, just described, the operating handle 75 has a lost motion connection with the cam 73, as illustrated in Fig. 3.

To secure "quick making" of the contacts a sliding bar 90 is provided generally parallel to the slots 26 of the bracket element 13 shown in Fig. 4, the bar 90 being carried on the pin 78 between the cam 73 and lever 83. A strap 92 is shown for additionally securing the bar 90 in position, the strap being secured to the adjacent bracket 13 as by a rivet 94' and screw 94" the latter permitting the strap to be swung aside about the rivet to permit assembly of the bar 90 into position. Near the lower end of the bar 90 is an inwardly extending pin 91 of a diameter substantially the same as the width of the slot 26 but easily slidable therein. The slot 26 has, near its lower end, a notch 92 which, in the closing operation of the switch, receives the pin 91 as a "hazard" and impedes the closing operation of the switch due to the fact that the end of the bar 90, which carries the pin 91, is drawn toward the notch by a suitable tension spring 93 connected at its opposite ends to the bracket 13 and bar 90 respectively.

The relationship of the switch contacts and blades at a time when the pin 91 engages the notch 92 is shown in Fig. 6, (full line showings of both parts). Referring to Fig. 5 and assuming that the cam 73 is being rotated in a counter-

clockwise direction (closing the switch) it will be seen that before the rollers 80 can enter the circumferentially extending portions 79b of the cam slots the pin 91 will have to be forced out 5 of the notch. This requires considerable force and the speed and pressure of the operator's hand on the handle 75 must be increased several fold after the pin encounters the notch 92 and before the switch contacts can be fully 10 closed. The detaining forces are released upon the pin slipping out of the notch but the excess pressure on the operating handle continues momentarily and is always sufficient to quickly close the contacts and seat the rollers 80 into 15 the circumferential portions of the cam slots, mechanically locking the contacts in closed position (see Figs. 3 and 7).

In connection with Fig. 5 it should be noted that the pin 91 is embraced by the notch 92 about 20 substantially one half of the pin circumference. In addition, a line through the axis of the pin 91 and axis of the pin 78, by which the bar 90 is carried, intersects the wall of the notch 92 beyond the pin in the direction of movement 25 toward contact making position. Thus when moved toward contact making position, as the pin 91 becomes fully seated in the notch 92, it becomes very difficult to unseat by pressure exerted on the bar 90 in the same direction. 30 Upon movement in the opposite direction, however, this line of force lies outwardly beyond the wall of the notch so that the pin can wedge the bar 90 to the right and release. It is for this reason that the speed of movement, as above 35 mentioned, is important. When operating at sufficient speed the pin 91 will not become fully seated in the notch as it passes the same and consequently the resisting wall of the notch will be operating well out on the sloping surface of 40 the pin 91 and the bar 90 will be moved onward to the right. A speed sufficient to cause the pin 91 to partially jump the notch 92, however, is also such as to assure that the contact making position will be reached as the operator cannot 45 even intentionally arrest movement from so great a speed between the time the pin 91 jumps the notch and the blades come into contact. When the pin 91 has moved to a position in which it has passed the notch 92 or is only partially seated therein so that it can be moved 50 onwardly and not restrained by the notch, the roller 80 will have passed the peak 79c of the cam and will promptly be locked in position for maintaining the contact relation of the contacts. 55

In heavier duty types of switches it is necessary to increase the gauge of the metal of the contacts to an extent such that the design of contacts illustrated in Figs. 4 and 7 is somewhat 60 impractical. In such cases, it is preferred to make the generally V-shaped movable contact members or blades in generally triangular shape, as illustrated in Fig. 8 at 100, the edges of the strip forming the blade being adjacent the arms 65 101 of the fixed contacts rather than opposite the fixed contacts as in the previously described arrangement. This modification of contacts preferably includes pressure affording spring elements such as 102 for the movable contact. The 70 spring 102, as illustrated, comprises a generally U-shaped strip of spring metal secured between the arms 103 of the movable contact, with the base secured to the closed portion of the strip forming the blade 100 as by a rivet or screw 75 (not shown). The movable contact may also be

provided with one or more reinforcing bars of copper e. g. as at 105 and 106, the portion thereof between the two wedge-shaped elements of a single contact bar being secured to the insulating cross bar 23 as by screws for example 5 (not shown) entering suitable openings in the reinforcing bar or bars. The stationary contacts may be made as shown in Fig. 8, separate arm strips being shown as secured in slots 107 in a base element of copper e. g. 108. 10

The arrangement of V-shaped contact elements may be reversed if desired; that is to say, the wedge members may be carried on the base block in some instances and the wedge receiving contact members carried on the cross head. 15

I claim:

1. In an electric switch, an insulating base, spaced contacts carried by the base, a frame carried by the base and surmounting the same, said frame having parallel slots at opposite sides 20 of the base, a cross head mounted in said slots and a bridging contact element carried on the cross head adapted to cooperate with the spaced contacts, operating means carried on said frame for moving the cross head inwardly and outwardly in the slots, and a hazard device carried by said cross head and comprising a bar pivotally mounted on the crosshead for swinging movement transversely of one of the slots and having a pin slidably in said one of the slots, 30 the latter slot having a notch adapted to receive the pin during its inward movement in a direction to close the switch, and resilient means yieldably urging the bar transversely of said one of said slots and opposing movement of the 35 pin out of the notch at a time when the electrical contacts are in approximately closed position.

2. In an electric switch, cooperable contactors, a carrier supporting one of said contactors and 40 movable toward and away from the other contactor for effecting the contact relation, a frame movably supporting said carrier, lineal guides for guiding said contactors to and from contact relation, an operating cam pivotally mounted 45 on the frame, a pin on the carrier engageable with the cam for operation of the carrier thereby and guided lineally in said guides, and the pivotal axis of the cam being spaced laterally from the path of travel of the pin, said cam 50 including a pin actuating cam surface extending generally radially from the pivot axis of the cam and shaped so that the force of the cam is applied generally parallel to the lineal guides during substantially the entire movement of the 55 carrier and a pin retaining surface extending generally circumferentially of the pivot axis of the cam, said circumferentially extending surface being engageable with the pin only in the closed position of the contactors and having a 60 shoulder for locking the pin in seated position, means yieldably urging said carrier away from contact making position, hazard means cooperable with the carrier when the carrier is moved almost to contact making position by the cam 65 with a predetermined force applied to the cam and opposing further movement toward said position, said hazard means being inoperative to oppose said movement consequent upon a predetermined greater force applied to and by said 70 cam for moving the carrier toward the contact position, said hazard means being positioned to operate just prior to the engagement of the pin by the pin retaining surface of the cam.

3. In an electrical switch, a pair of cooperable 75

contactors, a carrier supporting one contactor and being movable toward and away from the other contactor for effecting the contact relation, a frame, a guideway in the frame, a guide on the carrier accommodated in the guideway for guiding the carrier in a generally linear path to and from contact making position, a cam pivotally mounted on the frame for rocking movement, the pivotal axis being offset transversely of the path of travel of the carrier from the guideway, said cam having an operating surface coacting with the guide for moving the carrier to contact making position, said surface extending transversely of the path of travel of the guide in the guideway and being configured to extend at substantially right angles to the guideway at the instantaneous guide engaging portion of the surface throughout the major portion of the travel of the carrier, whereby the force and movement delivered by the surface is substantially directly parallel to and along the guideway.

4. In an electrical switch, a pair of cooperable contactors, a carrier supporting one contactor and being movable toward and away from the other contactor for effecting the contact relation, a frame, a guideway in the frame, a guide on the carrier accommodated in the guideway for guiding the carrier in a generally linear path to and from contact making position, a cam pivotally mounted on the frame for rocking movement, the pivotal axis being offset transversely of the path of travel of the carrier from the guideway, and positioned close to the level of the guide when the carrier is in fully open position, said cam having an operating surface coacting with the guide for moving the carrier to contact making position, said surface extending transversely of the path of travel of the guide in the guideway and being configured to extend at substantially right angles to the guideway at the instantaneous guide engaging portion of the surface throughout the major portion of the travel of the carrier, whereby the force and movement delivered by the surface is substantially directly parallel to and along the guideway.

5. In an electrical switch, a pair of cooperable contactors, a carrier supporting one contactor and being movable toward and away from the other contactor for effecting the contact relation, a frame, a guideway in the frame, a guide on the carrier accommodated in the guideway for guiding the carrier in a generally linear path to and from contact making position, a cam pivotally mounted on the frame for rocking movement, the pivotal axis being offset transversely of the path of travel of the carrier from the guideway, said cam having an operating surface coacting with the guide for moving the carrier to contact making position, said surface extending transversely of the path of travel of the guide in the guideway and being configured to extend at an angle to the guideway at the instantaneous guide engaging portion of the surface such that the greatest component of force of the surface on the guide is parallel to the guideway throughout substantially the entire movement of the carrier.

6. In an electrical switch, a switch box, a pair of cooperable contactors mounted therein, a carrier supporting one contactor and being movable toward and away from the other contactor for effecting the contact relation, a frame for supporting and guiding the movable contactor, a cam pivotally mounted on the frame for rocking movement and being cooperable with the movable contactor for moving the same to contact making position, said switch box having a front wall extending at right angles to the plane of the cam and a door hinged to the switch box and forming a continuation of the front wall when closed, said front wall having a slot, said cam having a portion extending through said slot to the outside of the box, said extending portion of the cam having a lug portion overlying said door when the door is in closed position and being engaged by said door upon opening thereof to move the cam to contact breaking position, and an operating handle connected to the outwardly extending portion of the cam.

FRED G. FAILE.
